DESIGN FOR A STOVE

Robert G. Rutledge, Ann Arbor, Mich.

Application March 4, 1940, Serial No. 90,673

Term of patent 14 years

To all whom it may concern:

Be it known that I, Robert G. Rutledge, a subject of the Dominion of Canada, residing at Ann Arbor, in the county of Washtenaw and State of Michigan, have invented a new, original, and ornamental Design for a Stove, of which the following is a specification, reference being had therein to the accompanying drawing, forming a part thereof, wherein:

Figure 1 is a perspective view of a stove embodying my new design; and

Figure 2 is a top plan view thereof on a slightly reduced scale.

The end of the stove opposite the end shown in Figure 1 of the drawing is substantially the same in design as the latter end.

I claim:

The ornamental design for a stove, substantially as shown and described.

ROBERT G. RUTLEDGE.
